UNITED STATES PATENT OFFICE.

WILLIAM GUY RUGGLES, OF NEW YORK, N. Y.

ORIENTATOR.

1,342,871.

Specification of Letters Patent.

Patented June 8, 1920.

Application filed April 16, 1917. Serial No. 162,589.

To all whom it may concern:

Be it known that I, WILLIAM GUY RUGGLES, a citizen of the United States, and resident of New York city, in the county of 5 New York and State of New York, have invented certain new and useful Improvements in Orientators, of which the following is a specification.

My invention relates in general to a device for supporting and changing, at will, the position of a person in space and specifically relates to a device for training those natural faculties which indicate to the mind that a person's head is rising or falling and 15 which indicates that the person's head is angularly disposed relative to a normal vertical position.

It is well known that there exists in the ear an organ, identified as semi-circular 20 canals which, when normally developed, contains floating bodies, which affect certain nerves to indicate change of position when a person's head is moved from its normal upright position.

25 It has been desirable in the medical profession for some time to develop this sense of position, for it has been noted that where these faculties are highly developed, there is a noticeable absence of vertigo, dizziness, 30 and other conditions, which particularly manifest themselves when the person is in an unusual position as on a high building looking down toward the ground.

With the recent development of the aero- 35 planing art, it has been found necessary to the successful operation of these machines, that the aviator have his position faculties rather highly developed. In this connection there has been developed an apparatus 40 for teaching the art of aeroplaning, including a seat which can be tilted into a limited angle, but this device is inoperative as it does not permit the aviator to accustom himself to all of the various angles into 45 which an aeroplane may be moved.

Accordingly, the primary object of my 50 invention is to provide a simple form of device for developing and training the functions of the semi-circular canals and incidentally to provide such a machine for training aviators to accustom themselves to any possible position in which they may be moved by the action of an aeroplane while in flight.

55 I attain this invention broadly by providing a chair or other support for the pa-

tient or aviator and mounting this support, so as to have universal articulation into any position relative to a fixed point of reference. 60

A further refinement of the invention is to provide two control stations, one operable by the patient or aviator under training and the other operated by an instructor, each station operatively connected to the 65 support so as to move the support into each of the three dimensional planes and to vary at will the angular position of the support relative to the normal upright position.

A further refinement of the invention re- 70 lates to an instrumentality for effecting a rising or falling movement of the support along the vertical line, or, in other words to move the relatively fixed point of articulation, so as to accustom the patient or aviator to the rising or falling effect produced by such a movement of his support. 75

For the purpose of accustoming the patient or aviator to a rarefied atmospheric condition, such as is present in the higher 80 atmosphere, the part of the device including the support is preferably designed to be inclosed within a casing operatively connected to some suitable pressure reducing means, designed to maintain a reduced and 85 variable pressure condition about the patient or operator in the support.

Various other objects and advantages of the invention will be in part obvious from 90 an inspection of the accompanying drawings and in part will be more fully set forth in the following particular description of one form of mechanism embodying my invention, and the invention also consists in certain new and novel features of construction and combination of parts hereinafter set forth and claimed. 95

Referring to the accompanying drawings: Figure 1 is a view in front elevation of a preferred embodiment of my invention 100 with an inclosing casing therefor shown diagrammatical and with the seat perpendicular;

Figs. 2 and 3 are detailed views of the 105 chair and its supporting ring, Fig. 2 showing the dipping ring at right angles to the position shown in Fig. 1 and the chair supporting ring turned to the left 45°, Fig. 3 showing the chair inverted and the supporting ring therefor turned to the left through 110 210° from the position shown in Fig. 1; and

Fig. 4 is a diagrammatic view of the

several parts together with their electrical connections.

In the following description and in the claims, parts will be identified by specific names for convenience of expression but they are intended to be as generic in their application to similar parts as the art will permit.

In the drawings there is shown a supporting platform 10 upon which is mounted an inclosing casing indicated diagrammatically by the upstanding walls 11 which casing is adapted to contain air at a pressure reduced from the external air pressure which reduction is effected by any suitable pressure reducing mechanism such as an air pump indicated diagrammatically at 12. Within the casing is the machine proper which includes a pair of upstanding columns 13, 14, tied together adjacent their upper ends by a girder 15. A rectangular gimbal ring carriage 16 is slidably mounted upon and positioned between the columns 13 and 14 and arranged to be guided between said columns in its vertical movements.

The carriage is supported and moved vertically by means of a hoisting arrangement including a pair of flexible cables 17 attached to opposite sides of the carriage and passed over pulleys 18 and 19 at the girder and both wound on a drum 20, forming part of a driving and brake mechanism supported from the platform 10 and constituting part of the carriage hoisting arrangement. This drum is of conventional form and is shown to be actuated from a motor 21 through multiplying gearing 22. Mounted within and movable vertically with the carriage is a gimbal ring construction which includes the azimuth ring 23 somewhat elliptical in form and journaled along its major axis at its upper end in bearings 24 and at its lower end in bearings 25 so as to permit a movement of the ring in a horizontal direction and about a vertical axis. This azimuth ring 23 has a pair of vertically disposed rings, one contained within the other and both disposed within its outline. The outer ring 26, hereinafter identified as the dipping ring 50 has opposite sides pivoted to the azimuth ring 23 by means of bearings 27 and 28 which permit a movement of the dipping ring about a horizontal axis intersecting the axis of movement of the azimuth ring. The inner ring 29 supports a chair 30 fixed thereto by means of clamps 31. The inner ring is mounted above and below the chair in bearings 32 and 33 which permit a movement of the inner ring about an axis intersecting the axis of movement of the dipping frame. It is apparent from the organization of gimbal rings that the ring 23 can swing about a vertical axis, the ring 26 can swing about a horizontal axis and the ring 65 29 can swing about its axis in whatever plane

it may be positioned by the single or combined movement of the other rings. The rings are controlled by reversible electric motors operatively connected to their respective rings so as to turn the same in either direction and over any desired angle of movement more or less than 360° as desired. A motor drive 34 controls the azimuth ring 23. A motor drive 35 controls the dipping ring 26 and a motor drive 36 controls the chair ring 29.

As these motor drives are all similar in construction, a detailed description of any one will be sufficient for all. The drive includes an electric motor 37 fixed to the armature shaft 38 on which is a worm 39 constantly meshing with a gear 40 which acts to form a shaft upon which is fixed a small gear wheel 41, meshing with a relatively large spur gear 42 fixed to a shaft 43 in turn fixed to the ring controlled by the particular motor drive, thus described. This gear connection is so designed that a small motor may be utilized and so connected to its controlling ring that the ring may be moved rapidly and quickly from one position to another.

The motors are electrically connected so as to be controlled by two stations, one accessible to the person occupying the seat 30, hereinafter identified as the machine station and the other accessible to the person occupying a seat 44, hereinafter identified as the instructor's seat and which is preferably positioned outside of the casing containing seat and its operating parts.

Where the device is particularly intended for the purpose of training aviators, it is desirable that these control stations be designed to follow, as far as possible, the conventional steering and control mechanism found on the type of machine which the aviator is training to operate. For this purpose the device illustrated is shown provided with steering wheels 45 and foot controls 46 and the several motors illustrated are connected to these steering wheels and foot pedals, so that the corresponding movement of the areoplane will be simulated when this control mechanism is actuated and will cause a similar sensation should the person occupying the seat 30 be actually in a machine of the character controlled by the mechanism adjacent his seat.

The motor drive 34 is wired to the two stations to control the compass direction horizontally which control is effected by means of the switch 47 at the instructor's station and by means of the switch 48 at the machine station. The motor drive 35 controlling the dipping motion is similarly controlled by means of the switch 49 at the instructor's station and by means of the switch 50 at the machine station. The motor 36 for causing an angular movement of the

seat supporting ring is controlled by the switch 51 at the instructor's station and by means of the switch 52 at the machine station.

5 Electric current to actuate the several motors is supplied from a suitable source indicated diagrammatically at 53 and leads by means of main conductors 54 and 55 to the swivel switches 47, 49 and 51 at the instructor's station, which are arranged in parallelism across the main conductors. The switches each include a relatively stationary member diagrammatically shown in Fig. 4, as a ring 56 and a relatively movable member, shown as a revolving disk 57 journaled to turn within the ring.

In order to prevent the machine station from actuating the several rings in opposition to the control of the rings from the 20 instructor's station, the current from the source 53 is led through circuit breakers 58, 59 and 60 indicated in dotted lines on the switches 51, 49 and 47, respectively, which are so arranged that when the movable element 57 of the switches is rotated 25 into any position from its normal position the circuit which leads to the corresponding machine switches 48, 50 and 52 is intercepted so that the machine station cannot control 30 the motors so long as the motors are under active control of the operator's station. The motor 34 is connected with the source 53 through the circuit breakers 58, 59 and 60, conductors 61, machine main conductors 62 35 to the switch 48. Conductors 63 lead from opposite sides of each switch to opposite sides of each motor controlled thereby as will be more particularly noted from the diagrammatic arrangement of the conductors shown in Fig. 4.

For the purpose of controlling the rise and fall of the gimbal ring carriage, the instructor's station is provided with an additional switch 64 arranged to actuate the 45 motor in either of its directions and thus control the rise and fall of the gimbal ring carriage.

The conductors connecting the two stations and connecting the several ring controlling motors with the source are assembled in a cable 65. The several conductors from the cable are led to the rings through communicator 66 constituting part of the several journals 24, 27 and 33.

55 In operation the patient or aviator will take his position in the chair and is strapped in position when it is desired to actuate the device violently or, when it is desired to turn over the dipping ring to simulate the loop-the-loop action of an aeroplane. The pressure condition within the casing is regulated to correspond with the conditions under which the instruction is to take place and by suitable manipulation of the 60 ring, either by the instructor or by the per-

son occupying the chair, the chair and person occupying the same is tilted or revolved about the respective axis of the gimbal ring construction, so as to take any position or move through any desired angle and through 70 any desired direction of movement.

It is possible by means of a device of this character, for the instructor to move the chair and person occupying the same into any desired position and then leave it to 75 the person in the chair to rectify this position and move himself back into any desired or into the normal position which he would take when in flight. It is apparent that by means of a device of this character all possible movements of an aeroplane may be 80 simulated and the occupant moved into any possible position relative to a point of reference.

It is also possible to vary this point of 85 reference vertically, so that a falling or rising effect may be produced simultaneously with a revolving into any desired angle or over any desired path within the limits of the machine.

90 Due to the worm drive connection it is possible not only to rotate the rings over an angle up to 360° but this angular movement may be repeated continuously and a spinning action produced about any of the 95 axis of movement.

It is apparent that the repeated use of a machine of this character will stimulate the semi-circular canals to a higher degree than is now possible with actual aeroplanes 100 practising, because the occupant of this machine may be moved into unusual angular positions and may be moved more rapidly than is possible with any known evolution of aeroplanes.

105 A further refinement of the method of treating or training by the use of this machine is to blindfold the patient or aviator so that the sense of direction may be sensitized without the assistance of the visual 110 senses. In this way the aviator when in a fog or intense darkness may be instinctively conscious of his position.

Having thus described my invention, I 115 claim:

1. In a device of the class described, the combination of a support for a person, an organization of pivotal means for mounting said support so as to have universal articulation in three planes at right angles 120 to each other about a relatively fixed point of reference and so as to permit the positioning of said support in any plane passing through said fixed point and mechanism acting on said organization for moving said supporting means into any desired position about said point of reference.

2. In a device for training a person's position senses, the combination of a support provided with means for securing the 130

person against falling from the support when inverted, means for mounting said support so that it may have universal articulation about any three axes intersecting 5 at right angles and selectively controlled means for varying at will the movement of said support about any one or a combination of said axes and for securing the support in any preselected position in space 10 relative to the point of intersection of said three axes.

3. In a device of the class described, the combination of a relatively fixed support, a seat pivotally connected thereto and 15 adapted to be inverted from its normal position, electrically actuated means for moving said seat from its normal position into an inverted position and means operable from said seat to restore the seat to a position 20 different from said inverted position.

4. In a device of the class described, the combination of a support for a person, a pivotal mounting for said support, means 25 acting on said support for moving the head of the person over a circular path of movement and about an axis of reference and power means operatively associated with the support for imposing another movement 30 on the same thereby to vary the position in space of said axis of reference.

5. A device for training a person's equilibrium functions, said device including means for supporting the person to be 35 trained, said means being mounted for universal articulation in all planes passing through a relatively fixed point of reference to dispose the supported person in all positions from an upright to an inverted 40 position and selectively controlled means operatively connected for varying at will the position of said supporting means.

6. A device for training a person's equilibrium functions, said device including a 45 plurality of pivotal means constituting a universal joint suspension adapted to provide a support for a person, said means being mounted for universal articulation through all angles up to 360°, and means 50 acting on said pivotal means for rotating at will any combination of said means to move the person through any plane passing through the point constituting the center of said universal joint suspension.

55 7. A device for training a person's equilibrium functions, said device including a gimbal ring construction with three concentric rings pivoted one to the other in order for suspending a person in space and 60 selectively controlled mechanisms connected to each of said three rings for moving the person while in an inverted or substantially inverted position through any plane or combination of planes passing through the 65 axis of said gimbal ring construction.

8. In a device of the class described, the combination of a seat having a normal position, a pivotal mounting for said seat, a driving means operatively connected to said mounting to rotate the seat over any angle 70 up to 360° and into an abnormal position in any one of a plurality of intersecting planes, and means accessible from the seat for restoring said seat into a position adjacent its normal position. 75

9. In a device of the class described, the combination with a seat having a normal position and means controlled from a point remote from said seat for moving the same into an abnormal position in any one of a 80 plurality of planes disposed at right angles to each other and a part of said means including a control therefor accessible from a position adjacent said seat for moving the same into a position different from said 85 abnormal position.

10. In a device of the class described, the combination of a seat and means for supporting the seat so as to provide universal articulation therefor, said means including 90 a gimbal ring construction, with each ring thereof free to rotate over an angle of 360°; means for rotating each of the rings through any angular movement and two sets of control mechanisms, each set operatively 95 adapted to control the movement of each ring.

11. In a device of the class described, the combination of a support for a person, an organization of pivotal means for mounting said support, so as to have universal articulation about a relatively fixed point of reference, mechanism for moving said supporting means into any position about said point of reference, and two sets of 100 control mechanisms, one of which is spaced from the device and the other of which is carried by the device, each set connected to said seat moving mechanism to effect a movement therefor and thus control the 110 position of said supporting means. 105

12. In a device of the class described, the combination with means for supporting a person, means for mounting said supporting means so as to have universal articulation, said supporting means including a gimbal ring construction including three rings and means for rotating at will any of the rings of said gimbal ring construction over any angle up to 360°. 115 120

13. In a device of the class described, the combination of three concentrically disposed rings with each inner ring pivotally mounted to its next adjacent outer ring, and the outermost ring pivotally mounted, 125 power means connected to the innermost ring to revolve the same and a control operatively connected to said power means to cause the same to function.

14. A device for training a person's 130

equilibrium functions, said device including means for supporting a person, said means being mounted for universal articulation and including a gimbal ring construction, 5 independent means connected to each of the rings to rotate the same through any angular movement up to 360° and two sets of control mechanisms, each set operatively connected to control the movements of each 10 of the rings.

15. In a device of the class described, the combination of a seat, a construction including a plurality of pivotally mounted rings, one of said rings pivotally supported by 15 the other ring and in turn constituting a means for supporting said seat so as to have universal articulation, a source of power operatively connected to each of the rings and a control for said sources of power 20 movable with one of the rings to vary the position of the same at will.

25. In a device of the class described, the combination of a seat, a gimbal ring construction for supporting said seat so as to have universal articulation, motors operatively connected to each of the rings to vary the position of the same at will and two control stations, each operatively connected to control the position of each of the rings 30 and means for disconnecting one of the stations while the other station is in active control of any one of the rings.

35. In a device of the class described, the combination of a ring pivotally mounted to revolve about an axis, means acting on the ring for shifting said axis, a seat supported from said ring, an electric motor for revolving said ring about its axis in all positions of the same and a circuit controlling 40 switch for said motor carried by said ring.

45. In a device of the class described, the combination of a seat for supporting a person in space, three sources of power, means coupling each of said sources of power to the seat to cause each source of power to rotate the seat in a plane at right angles to the planes in which it is rotated by each of the other sources of power and a control for selectively causing one or more sources of 50 power to function.

55. In a device of the class described, the combination of a pivotal frame, a seat supported from said frame, an electric motor for revolving said frame, two separated controls for said electric motor and means for disconnecting one of said motor controls while the other is in circuit closing position to control the motor.

60. In a device of the class described, the combination of a support for a person, means for preventing bodily movement of said support in any horizontal direction while permitting a movement of said support along a vertical line, pivotal means for 65 mounting said support to provide for move-

ment thereof into any desired position about a point in said vertical line, and means acting on said support for rotating the same into any desired position about said point.

21. In a device of the class described, the combination of a support for a person, means for preventing bodily movement of said support in any horizontal direction while permitting a movement of said support along a vertical line, means for mounting said support to provide for movement thereof into any desired position about a point in said vertical line, means acting on said support for rotating the same into any desired position about said point, and means 70 acting on said support for moving the same vertically.

22. In a device of the class described, the combination of a support for a person, means for preventing bodily movement of said support in any horizontal direction while permitting a movement of said support along a vertical line, means for mounting said support to provide for movement thereof into any desired position about a 75 point in said vertical line, means acting on said support for rotating the same into any desired position about said point, and means acting on said support for moving the same vertically. 80

23. In a device of the class described, the combination of a support for a person, means for preventing bodily movement of said support, in any horizontal direction while permitting a movement of said support above a vertical line, means for mounting said support to provide for movement thereof into any desired position about a point in said vertical line, means acting on said support for rotating the same into any desired position about said point, means acting on said support for moving the same vertically, and a control for said last named 90 means, said control being spaced from the seat whereby the control of the vertical movement of the seat is not available to the person in the seat.

100

24. In a device of the class described, the combination of a support for a person, means for preventing bodily movement of said support in any horizontal direction while permitting a movement of said support along a vertical line, means for mounting said support to provide for movement thereof into any desired position about a point in said vertical line, means acting on said support for rotating the same into any desired position about said point, a control station provided with controlling mechanism for moving the support vertically and for rotating the same. 110

115

120

125

130

port and provided with mechanism for rotating with said support.

25. In a device of the class described, the combination of a gimbal ring construction, 5 a seat supported from the inner ring of said construction, a carriage for supporting said gimbal ring and a plurality of motors, each ring provided with one of said motors and said carriage provided with a motor to move 10 the same and a control station for selectively controlling at will any one or more of said motors.

26. In a device of the class described, the combination of a gimbal ring construction, 15 including three concentric rings with each inner ring pivoted to the next adjacent outer ring and with the outermost ring pivotally mounted, a seat supported from the inner ring of said construction, a carriage for supporting 20 said gimbal ring construction, a plurality of motors, each ring provided with one of said motors, a control station movable with the seat for selectively controlling at will any one or more of said motors, and 25 means independent of said control for intercepting the circuit to said motors.

27. In a device of the class described, the combination of a gimbal ring construction, a seat supported from the inner ring of said 30 construction, a plurality of motors, each ring provided with one of said motors, a plurality of control stations, one carried by the seat and the other fixed in position and each provided with a switch for each of 35 said motors.

28. In a device of the class described, the combination of a gimbal ring construction, a seat supported from the inner ring of said construction, a carriage for supporting 40 said gimbal ring construction, a plurality of motors, each ring provided with one of said motors and said carriage provided with a motor to move the same, a plurality of control stations, one of said 45 stations provided with a switch for each of said motors and the other station provided with a switch for the ring controlling motors and means at one of the stations for making certain of the switches inoperative.

50. 29. In a device of the class described, the combination with a seat, an inclosing casing therefor, means for rocking the seat and air pressure reducing means for reducing the air pressure in said casing, said pressure reducing means coacting with said seat rocking means to simulate the effect produced on an aviator while traveling in an aeroplane at high altitudes.

60. 30. In a device of the class described, the combination with a seat and means for moving the seat into all possible positions in which the aviator's seat in an aeroplane may be positioned while in flight, an inclosing casing therefor, means including pressure reducing means for reducing the air pres-

sure in said casing thereby to simulate the effect produced on an aviator while traveling in an aeroplane at high altitude and while in the different positions in space.

31. A device for training the coördination of those natural faculties which indicate to a person's mind his appreciation of his position while inverted in space with the proper muscular effort to control mechanism to effect a change in his position, the combination of means for supporting the person fixed against movement relative to a point of reference, power means operatively connected to said supporting means for moving the supported person in any desired direction about said point to and from an abnormal position beyond a tilted position and a control for said power means accessible to the person while in the inverted position.

32. In a training device, means for supporting a person while moving in space, power means operatively connected to said supporting means for spinning a part of the person in space and in a circle about a point of reference and control means accessible to the supported person operatively connected to said supporting means for selectively defining the path of movement of the person while spinning.

33. In a training device for resisting the tendency of a person to become dizzy when subjected to a rotary movement in space, the combination of rotatably mounted means for supporting the person, power means for spinning the supported person and a control 100 for regulating the spinning movement.

34. In a training device for resisting the tendency of a person to become dizzy when subjected to a rotary movement in space, the combination of rotatably mounted means for supporting the person, power means for spinning the supported person over a closed circuit which is disposed in more than one plane and a control accessible to the supported person for regulating the spinning 110 movement.

35. In the art of training those involuntary natural faculties which are responsive to nerve impulses from that part of the semi-circular canal system which indicates 115 to a person a correct conception of his position in space when his head is in an inverted position, in distinction from the similar space senses active when the person is in a normal upright or horizontal position, the 120 process which includes the step of intentionally causing the person to move bodily and repeatedly into a substantially inverted position while being held in uniform spaced relation to a fixed point and causing the 125 person, when so inverted, to express by an overt and voluntary act some evidence of his appreciation of his abnormal position.

36. In the art of training those natural faculties which indicate to a person's mind 130

that his head is rising or falling and which indicate that the person's head is inverted or substantially inverted relative to the normal vertical upright position, the process 5 which consists in moving the person from the normal, upright position into different abnormal positions beyond a tilted position with a controlled speed substantially free of gravitational, centrifugal and other forces 10 which may tend to affect the desired controlled movement of the person in space.

37. In the art of training those natural faculties which indicate to a person's mind that his head is rising or falling and which 15 indicate that the person's head is angularly disposed or inverted relative to a normal vertical upright position, the process which consists in moving the person from the normal, upright position into different abnormal positions beyond a tilted position and along 20 a definite, preselected path and causing the person when so positioned to express by an

overt act his identification of his abnormal position.

38. In the art of training a person to co- 25 ordinate the mental instinct to assume a normal upright position when in an abnormal inverted or substantially inverted position, with a muscular effort to actuate control mechanism to restore the person to a normal 30 upright position, the process which consists in repeatedly placing the person in said abnormal position while in relative short visual range of some stationary object and in causing said person to move into some 35 other abnormal position when any muscular effort is exerted on the control mechanism other than such an effort as will restore the person to his normal upright position.

Signed at New York city, in the county of 40 New York and State of New York, this 11th day of April, A. D., 1917.

WILLIAM GUY RUGGLES.
